UNITED STATES PATENT OFFICE

2,015,489

AIR CONDITIONING FOR CARS

Frank O. Marshall, Chicago, Ill., assignor to
 Pullman Car and Manufacturing Corporation,
 Chicago, Ill., a corporation of Delaware

Application November 9, 1932, Serial No. 641,823

7 Claims. (Cl. 62—139)

The principal object of this invention is to supply a passenger car with cool, clean air at a minimum cost and with the least possible changes in the car and its regular equipment.

Generally speaking this is accomplished by—
 (1) Evaporating water with a copious current of air drawn from and returned to the outside of the car whereby the latent heat of evaporation amounting to 1080 B. t. u. per pound is taken up and ejected from the car;

(2) Passing the air supply for the car in heat exchange relation with the evaporation area whereby the air supply is cooled without increasing its moisture content; that is, its wet and dry bulb temperatures are lowered but its constituent of water vapor is not increased; and

(3) (When conditions make it appropriate), subjecting the cooled air supply to further cooling to reduce its dry bulb temperature as by treating it with a spray of cool or cold water, which will also thoroughly clean the air.

Further objects and advantages of the invention will become apparent as the disclosure proceeds and the description is read in connection with the accompanying drawings which are largely diagrammatic and in the main illustrative.

Fig. 1 is part side elevation and part longitudinal section of a Pullman sleeping car, equipped according to the invention;

Figs. 2 and 3 are vertical sections taken on the lines 2—2 and 3—3 respectively of Fig. 1;

Fig. 4 is an enlarged longitudinal sectional view similar to the upper portion of Fig. 1, and

Fig. 5 is a transverse sectional view through the upper portion of the car looking downward. But these drawings and the specific description are used for the purpose of disclosure only and are not intended to indicate the scope of the invention, and it is realized that the same may be embodied in various forms and applied to various uses.

General description

The car structure shown is conventional for Pullman sleeping cars, the details of which vary widely and are well known.

The floor plan shown in Fig. 388, page 302 of the Car Builders Cyclopedic, 1925, may be assumed without addition to the drawings, although the apparatus here illustrated was designed and first applied to the Pullman sleeping car Gloucester, which differs from the floor plan in the Car Builders Cyclopedic in some features not material here.

The conventional sleeping car has a clearstory and includes a main roof or lower deck 10, deck sides 11 and an upper deck 12 (see Figs. 2 and 3).

There is a vestibule 13 adjacent to each end connected with the passenger seating space 14 by a passage 15 (Fig. 3) alongside a lavatory space 16. The roof zone above the passageway and lavatory is, in the main, unoccupied and, for that reason, is selected as the location of the principal parts of the air conditioning apparatus.

The passenger space is supplied with 2500 cubic feet of air per minute which enters inlets 17 (Fig. 5) through one deck side 11, under the impulse of a fan 18 that forces it through a bank of tubes 19, then through a spray chamber 20 counter to a cool water spray from whence it escapes through eliminator plates 21 into a delivery conduit 22 running lengthwise to the passenger space, and provided with two series of openings 23 by which the air is distributed uniformly and without draft.

Five thousand (5000) cubic feet of air per minute used for evaporation enters the inlets 24, circulates around the tubes 19 and through a water spray, falling on them, escapes between 25 the eliminator plates 25 under the impulse of a fan 26, which forcibly ejects it through outlets 27 through the deck side opposite to that where it entered.

From this it will be seen that the air supply for the passengers is first cooled in the tubes 19 without adding to its moisture content (whereby its wet and dry bulb temperatures are reduced) and then is further cooled and washed by running counter to a spray of cool or cold water (whereby its dry bulb temperature is further reduced) and then is delivered to and distributed in the passenger space. The quantity of water discharged from the last mentioned spray is preferably limited so that additional cooling is obtained without permitting the air to become saturated with moisture so as to produce undesirable humidity conditions.

As a general rule, the cooling thus obtained will be sufficient for the comfort of the passengers, but under extreme conditions further cooling may be desired, and can be had by treating the spray water with ice or mechanical refrigeration apparatus, which the knowledge of the art will readily supply.

Specific description

The inlets 24 are made through conventional ventilator openings in the side deck 11, and are fitted with louvres 28 and screen 29. The con-

struction of the inlet passages may be varied so widely that a specific description is deemed inappropriate.

They deliver into what may be called, for convenience, a treatment chamber or evaporation chamber, which takes, roughly, the form of a six-sided box, including a curved top 30 (Fig. 3), upright sides 31, 32, upright ends 33, 34, and a bottom 35 sloped to a drain 36, leading into a tall receiving tank 37, located in the wall between the passageway and the lavatory.

The gently curved exit, or outlet 38, (Fig. 5) through the side wall 32, forms the inlet to the centrifugal fan 26, equipped with a rope drive 39, leading to a two-horse power motor 40. The fan 26 delivers into a discharge passage 41, leading to the three outlets 27.

The tubes 19 pass through the ends 33 and 34, and are made airtight therewith, to prevent any leakage of evaporation air or water into the path of the supply air. The tubes are of thin copper, tinned inside and outside, and their ends are upset and brazed to the walls 33 and 34 which, like the other parts of the box-like chamber, are of galvanized iron. The number and arrangement of the tubes 19, shown in Fig. 3, will serve as a guide, but of course, may be varied quite widely, according to the conditions.

The spray water for evaporation is delivered by a pipe, or header, 42, extending lengthwise above the tubes 33, and equipped with five pairs of nozzles 43.

A pump 44, mounted beneath the car, supplies fifty gallons of water per minute under ten pounds pressure, drawn through piping 45 from the bottom of the tank 37 and delivered through piping 46 to the header 42. The pump used to force the water through the circuit is of any suitable type, and is driven by three-quarter horse power electric motor.

Water lost by evaporation is replenished from an auxiliary tank 47, also supported beneath the car and connected with the wash water pressure system that is familiar to all car builders.

A pipe 48 (Fig. 1) of this system is provided with a magnetically operated valve 49 of suitable make which is controlled by a snap switch 50, operated by a float 51 in the tank 37. Piping 52 leads from the valve 49 to the upper portion of the tank 37.

As shown best in Fig. 3, the eliminator plates 25 extend about half-way up from the bottom 35 of the evaporation chamber and terminate against the lower edge of a baffle 53, extending lengthwise to the evaporation chamber between the ends 33 and 34.

Adjacent to the outlet 38 for evaporation air and below it is a surge baffle 54 to deflect water in the bottom of the chamber.

The spray chamber 20 is defined by sides 55 and 56 extending between the end 34 of the evaporation chamber and a low wall 57, all of which are connected by a bottom 58 to form a sump or tank for the spray water. Piping 59 connects this tank with the pipe 48 of the pressure system, and the flow is controlled by a float valve 60 located in the tank.

Another pump 61, driven by a three-quarter horse power electric motor, draws fifteen gallons of water per minute from this tank through piping 62, and delivers it under twenty pounds pressure through piping 63 to a header 64 arranged transverse to the spray chamber and equipped with a plurality of spray heads 65.

A false bottom 66 is arranged to catch any

leakage from the evaporation chamber and the spray chamber, and piping 67 is supplied to conduct the water away.

The inlets 17 for air to be conditioned are provided with louvres 68, having some dust excluding devices 69, here shown as wire screens, but when the cleaning and cooling spray is omitted they should be actual filters. The details of the inlet passages are a matter of choice and may, indeed, be inserted through the vestibule ceiling 70 instead of the deck side 11.

The air flow is induced by the centrifugal blower 18, driven by one horse power electric motor 11 at 1750 revolutions per minute. The delivery spout of the blower is extended by a funnel shaped housing 72, which is made fast to the end 33 of the evaporation chamber so as to conduct the air into the ends of the tubes 19.

These tubes are made as thin as is practicable and their interior surface is increased by plates 20 or fins 73 extending lengthwise and soldered or brazed to the tubes. For general purposes the tinned copper aforementioned, is more suitable, but where neither alkali nor salt is in the air aluminum may be used to advantage.

Eliminator plates 21 are arranged in a funnel shaped conduit 74 (Figs. 1 and 4) leading to an opening in a bulk head 75, and delivering to the conduit 22. This conduit is formed by inserting a longitudinal plate 76 stayed at the middle by braces 77 and joined at the sides by the perforated angle pieces 78. However, the delivery conduit and such are matters of selection.

Power for operating the motors will ordinarily be drawn from the axle generator system most commonly used on cars but, of course, may be supplied otherwise as conditions may suggest. The location and arrangement of switches, thermostats, and other control devices is a matter of choice.

As a general thing it will be convenient to control the two water circuits and the two air circuits separately, for in some instances proper ventilation will be had without operating all of the apparatus. For example, on one part of a run it will be sufficient to operate the blower 18; at a later time it will be helpful to start the spray in the chamber 20, and still later to put the evaporating chamber in full operation. On runs between Chicago and Los Angeles a car equipped as here disclosed has been found clean and comfortable all the way. As a general thing the air is delivered at a reduced wet bulb temperature and a materially reduced dry bulb temperature.

The efficiency of the system will, of course, be greatly affected by the insulation provided, but the skill of the car builder will be sufficient to supply all such details without any description.

I claim as my invention:

1. In apparatus for cooling air in a passenger car, a treatment chamber between deck sides, an inlet and an outlet through the deck side connecting the chamber with the outside air, means for sending a copious draft of outside air through the chamber, a heat exchanger comprising thin walled tubes traversing the chamber, and exposing large surface areas to the draft, means for spraying the tubes with water, and means for sending a current of air through the tubes into the car.

2. In a passenger car having a passenger space, a lavatory and a passageway at one side of the lavatory, a treatment chamber above the lavatory in communication with the outside air, a tank between the lavatory and the passageway and

connected with the bottom of the chamber, a heat exchanger in the chamber having passages in line of communication with the outside and the passenger space, means for drawing water from the tank and spraying it on the heat exchanger, means for forcing a copious current of outside air over the heat exchanger, and means for passing air through the heat exchanger and into the passenger space.

10 3. In a passenger car having a passenger space, a lavatory and a passageway at one side of the lavatory, a treatment chamber above the lavatory in communication with the outside air, a tank between the lavatory and the passageway and connected with the bottom of the chamber, a spray tank beneath the car in communication with the first tank, means for forcing water from the spray tank to the first tank, means for controlling the water level in the first tank, a heat exchanger in the chamber having passages in line of communication with the outside and the passenger space, means for drawing water from the tank and spraying it on the heat exchanger, means for forcing a copious current of outside air over the heat exchanger, and means for passing air through the heat exchanger and into the passenger space.

15 4. In a passenger car, a blower, a tubular heat exchanger and a spray chamber in series between the outside and the passenger space, means for discharging a spray over the heat exchanger, means for collecting the excess water from the

heat exchanger spray and using it as a spray in the spray chamber, and means for passing a copious current of outside air over the heat exchanger.

5 5. In a passenger car having a main roof, an upper deck and deck sides, an evaporating chamber having an inlet through one deck side and an outlet through the other deck side, a heat exchanger in the chamber, means for wetting the heat exchanger, means for passing a copious current of air in at the inlet through the chamber 10 over the wetted heat exchanger and out at the outlet, and means for passing air through the heat exchanger and into the car.

6. The method of conditioning air by the evaporation of water which consists in passing the 15 air to be cooled in heat exchange relation, but not in direct contact with a spray of water through which a copious draft of outside air is passed and using the excess water from said spray for further cooling the conditioned air by direct contact with 20 said air.

7. In apparatus for cooling the air, the combination of a treatment chamber, a metal heat exchanger in said chamber providing a passage for air through the heat exchanger, a spray 25 chamber, means for forcing air through said heat exchanger and spray chamber, means for circulating air in copious quantities over the exterior of the heat exchanger, and a closed circuit for discharging water over said heat exchanger and 30 thence through the spray in the spray chamber.

FRANK O. MARSHALL.
